UNITED STATES PATENT OFFICE.

WILLIAM CLANCY, OF ANACONDA, MONTANA.

APPARATUS FOR SCREENING AND CONCENTRATING ORES.

SPECIFICATION forming part of Letters Patent No. 508,282, dated November 7, 1893.

Application filed February 15, 1893. Serial No. 462,439. (No model.)

To all whom it may concern:

Be it known that I, WILLIAM CLANCY, a citizen of the United States, and a resident of Anaconda, in the county of Deer Lodge and State of Montana, have invented certain new and useful Improvements in Apparatus for Screening and Concentrating Ores; and I do hereby declare that the following is a full, clear, and exact description of the invention, which will enable others skilled in the art to which it appertains to make and use the same, reference being had to the accompanying drawings, which form a part of this specification.

15 My invention relates to improvements in machines principally designed for screening and concentrating ores, although it may be employed for all purposes which screening machines are generally used for, and is intended as an improvement upon the invention for which Letters Patent were granted to me on May 31, 1892, No. 476,035.

20 The object of the invention is to provide an improved screening apparatus in which twigs, leaves and other rubbish which are usually present with the ore may be separated therefrom and removed from the machine in an expeditious and efficient manner, thereby preventing the same from being carried over to 25 the settling tanks.

The invention consists in the novel construction and combination of parts hereinafter fully described and claimed.

30 In the accompanying drawings, Figure 1 is a side elevation of a machine constructed in accordance with my invention. Fig. 2 is an end view of the same. Fig. 3 is a similar view looking in the opposite direction. Fig. 4 is a central longitudinal section. Fig. 5 is a central cross section. Fig. 6 is a horizontal section, on the line x, x , Fig. 5.

35 In the said drawings the reference numeral 1 designates end uprights which support the machine. Near the lower ends of these uprights are brackets 2 in which are journaled eccentric pinions 3, which mesh with cogged rims 4, of a drum 5. This drum comprises the cast iron heads 6, with which the rims 4 are made integral and annular flanges 7, which 40 form guides for the eccentric pinions. It will 45 be noticed that these pinions are so arranged

that as the drum is rotated as hereinafter described, a rocking motion will be communicated thereto. The heads 6 are connected together by V shaped horizontal ribs 8, and are provided with a covering 9 of wire gauze or perforated metal. The central openings in the heads at the lower portions are closed by means of plates 6^a.

50 Secured to these plates is a tapering trough 10, one end being considerably larger than the other. This trough extends the full length of the drums and at its upper side is provided with a slot or opening 12, extending from end to end thereof. In the interior of the drum at one side is a segmental shield 13, consisting of a curved metal plate, the upper end of which terminates in close proximity to the slot in the trough. Located in the drum is a feed flume 14, consisting of a horizontal board or plate extending from end to end thereof, and provided with a diagonal plate 15, of wire gauze or perforated metal of coarse mesh.

55 Secured to the uprights 1, near their upper ends are brackets 16, in which are located movable journal boxes 17, in which is journaled a fan shaft 18. Intermediate of the journal boxes and the upper ends of the brackets are springs 19, against which bear screw rods 20, by which their tension may be regulated. Connected with a horizontal rod 21, is a fan casing 22, having open ended heads 23, through which the shaft 18 of the fan 24 passes. This shaft is made in two parts or 60 provided with an extension 18^a, connected together at 18^b by a universal joint. This extension is connected with a fan casing 25, having a fan 27, and its outer end is journaled in a slot in the upper end of an upright 65 or standard 28. The object of this slot, the vertically movable journal and the universal joint connection of the two part shaft is to permit the fan casing and fan shaft to have a slight vertical movement without correspondingly moving the pulley on said shaft. The fan casing 25 is provided with a downwardly extending pipe 29, communicating with the tapering trough.

70 Journalized in a bracket 30 carried by an upright 31, is the main driving shaft 32, having a driving pulley 34, which is to be connected

with any suitable motor, and a pulley 35, connected by a belt 36 with a pulley 37 on the shaft 18. The shaft 32 is connected with a shaft 38, journaled in the vertically movable bearing 17 of one of the brackets 16 by means of a spring 39. This shaft 38, carries a pinion 42, which meshes with the cogged rims 4, of drum 5. By means of the spring connection between shafts 32 and 38, the latter can move vertically without correspondingly moving shaft 32.

The bearing 17 at the opposite end of the machine carries a shaft provided with a pinion 42, which meshes with the cogs on the drum at that end.

The operation will be readily understood. The material to be screened is fed to the flume, and the twigs, leaves and other rubbish will be thrown toward the segmental screen and will be caught by the ribs of the drum and carried around and delivered into the trough at the upper end of the machine.

Having thus described my invention, what I claim is—

1. In a screening apparatus, the combination with the rotatable drum comprising the heads, the V-shaped ribs connecting the same and the reticulated covering, of the tapering trough having a slot or opening in its upper side, the segmental shield in said drum, the feed flume, the shaft located above said drum having a fan and a fan casing communicating with the drum, the extension connected with said shaft by a universal joint, and the vertically movable fan and fan casing carried by said extension and communi-

cating with the feed flume, substantially as described.

2. In a screening apparatus, the combination with the rotatable drum comprising the heads, the ribs connecting the same, and the reticulated covering, of the tapering trough having a slot or opening in its upper side, the segmental shield in said drum, the feed flume, the two part shaft located above said drum, connected together by a universal joint, the fan and its casing communicating with said drum, the vertically adjustable fan casing and fan communicating with the flume, the shaft provided with a driving pulley, the vertically movable shaft having a pinion meshing with cogs on the rim of the drum and the coiled spring connecting said shafts, substantially as described.

3. In a screening apparatus, the combination with the uprights, the drum and means for rotating the same, of the eccentric pinions journaled in said uprights and the cogs on the drum meshing therewith, substantially as described.

4. In a screening apparatus the combination with the rotatable drum of the feed flume comprising the horizontal board or plate and the diagonal plate of wire gauze, substantially as described.

In testimony that I claim the foregoing as my own I have hereunto affixed my signature in presence of two witnesses.

WILLIAM CLANCY.

Witnesses:

JAMES O'HARA,
THOMAS MAXWELL.
